SWITCH CONTROL AND INDICATION SYSTEM

Paul M. Brannen, Duquesne, Pa., assignor to The Union Switch & Signal Company, Swissvale, Pa., a corporation of Pennsylvania

Application January 30, 1947, Serial No. 725,231

3 Claims. (Cl. 246—219)

1

My invention relates to railway switch controlling and indicating apparatus and particularly to apparatus for controlling and indicating an electrically operated switch.

Where a considerable distance separates the control point and the switch operated therefrom, it is desirable to use the least number of conductors between the two locations.

An object of this invention is to provide an improved switch control and indicating system of the type described in which only two conductors are used for the purposes of controlling the switch and indicating its position, and in which the two conductors at times provide a channel for controlling the position of an electrically operated switch, in addition to carrying the energy for operation of the switch motor, and at other times provide a channel for indicating the position of the switch.

Another object of the invention is to provide improved switch control and indication means which may be employed in situations in which the energy for operating the switch is provided by a hand operated generator at the office.

In practicing my invention, I provide two conductors extending from the control point, or office, to the switch location, which are normally connected at the office to a polarized indication relay, and at the switch location, to a low voltage source of energy through circuit controlling apparatus for providing an indication of the position of the switch.

When the hand generator at the office is operated and its voltage reaches a predetermined value, it energizes a transfer relay at the office, causing the two conductors to be disconnected from the indication relay and to be connected with the hand generator terminals through a pole changing device. Accordingly, a relatively high voltage of one polarity or the other is placed across the conductors, causing a polar neutral switch control relay at the switch location which is connected across the conductors to become energized. The neutral contacts of this relay thereupon pick up to connect the two conductors to the motor of the electric switch, which then becomes energized in a direction determined by the polar contacts of the switch control relay and operates the switch to one position or the other, depending on the polarity of the supplied energy. In addition, when the neutral contacts of the switch control relay are picked up they interrupt the connection between the line wires and the source of energy for operating the indication relay at the office.

2

After the switch has completed its operation, and the operator stops the operation of the hand generator, high voltage is no longer supplied to the relays at the office and field, and they release, connecting the indication apparatus to the conductors, which then operates to indicate the present position of the switch. I also provide means for interrupting the supply of energy to the motor when the switch position corresponds to that of its control relay, and also in the event of an overload.

Other objects of the invention and features of novelty will be apparent from the following description taken in connection with the accompanying drawing.

I shall describe a preferred form of switch control and indication system embodying my invention, and shall then point out the novel features thereof in claims.

20 Referring to the accompanying drawing, which is a view of a preferred embodiment of my invention, there is shown at the office a hand operated direct current generator G, which may be operated to supply energy of a relatively high voltage to conductors 9 and 10 by a circuit including the pole changing contacts 11 and 12 of a lever L and front contacts 15 and 16 of transfer relay WCR. Back contacts 15 and 16 of relay WCR normally connect the winding of polarized indication relay WPR, which will operate on a relatively low voltage, to conductors 9 and 10. The winding of relay WCR is connected across the generator G and its operating characteristics are such that it will pick up only after the voltage of the energy supplied by the generator has reached a predetermined value. Contacts 17 and 18 of relay WPR are illustrated as controlling indication lamps 49 and 50, supplied with energy from a suitable source, not shown, whose positive and negative terminals are denoted as BX and CX, respectively, but these contacts or other contacts on the relay may be employed to control other types of indication means or may be employed for any other appropriate purpose.

45 At the field location there is shown a track switch W, which is moved between a normal and a reverse position by means of a motor M which is designed to operate on direct current. The motor drives the switch through suitable mechanism, not shown.

Associated with the motor are a switch control relay WR, a quick acting relay WCPR, and an overload relay OR. The winding of relay WR, which is connected across conductors 9 and 10, has a high resistance, so that a relatively high

voltage must be supplied in order for it to operate, and is governed by a back contact 29 of relay OR.

The equipment is shown in the condition which it assumes when the switch W and the control lever L are in their normal positions, and the hand generator is not being operated.

As there is no energy supplied to the winding of transfer relay WCR, its back contacts 15 and 16 connect the winding of indication relay WPR to the conductors 9 and 10. Relay WPR is a polarized relay having a low resistance winding, and will operate on energy of relatively low voltage. At this time relay WPR is energized by a suitable low voltage source of direct current at the field station, such as a battery, not shown, whose positive and negative terminals are denoted as B and C, respectively. This circuit is traced from positive terminal B, through blocking rectifier K, over normal polar contact 21 of relay WR, normal contact 22 of the switch indication circuit controller, back contact 23 of relay WPCR, back contact 24 of relay WR, over conductor 10, back contact 15 of relay WCR, through winding of relay WPR from left to right, over back contact 16 of relay WCR, conductor 9, back contact 25 of relay WR, normal contact 29 of the switch indication circuit controller, over normal polar contact 30 of relay WR, and through the resistor R to negative terminal C. The winding of relay WPCR has a high resistance, and the energy supplied by the indication source is insufficient to cause the relay to pick up its contacts. Accordingly, relay WPR is energized with energy of normal polarity and its neutral contact 17 is picked up while its polar contact 18 occupies its normal position, and these contacts establish a circuit to light normal indication lamp 49 to show that the switch occupies its normal position.

Contacts 22 and 29 of the switch indication circuit controller are operated by the movement of the switch so that when the switch is in its normal position the normal contacts are closed and when the switch is in its reverse position the reverse contacts are closed, while both contacts are open when the switch is in transit. Resistor R is a current limiting resistor which limits the flow of high voltage energy through the source of indication energy should the operator operate the hand generator without operating lever L.

If the operator desires to move the switch W to its reverse position, he may do so by moving the control lever L to its reverse position and operating the generator. When the generator output voltage becomes sufficient, relay WCR picks up and disconnects wires 9 and 10 from the winding of relay WPR and connects these wires to the generator through contacts 11 and 12 of the lever L. Accordingly, relay WPR is released, and contact 17 interrupts the supply of energy to normal indication lamp 49. Positive high voltage is supplied over reverse lever contact 11, front contact 15 of relay WCR, through conductor 10, over back contact 24 of relay WR, back contact 23 of relay WPCR, normal circuit controller contact 22, and over normal polar contact 21 of relay WR, but is prevented from causing the flow of current to terminal B by the rectifier K which is poled to permit current to flow from terminal B to polar contact 21, but prevents the flow of current in the opposite direction.

The high voltage present across the terminals of relay WPCR causes this relay to pick up quickly and its back contact 23 in the circuit previously traced disconnects the source of energy for the switch indication from the control

conductors 9 and 10, and as a result prevents overloading of the indication circuit by the high voltage operating energy until such time as relay WR picks up and further isolates the indication circuit from the line circuit, while the relay WR now receives sufficient energy from the control conductors 9 and 10 to operate its contacts, and the polarity of the energy supplied is such that its polar contacts move to their reverse position, and its neutral contacts pick up, interrupting the connection between the conductors 9 and 10 and that portion of the circuit including the source of indication energy and the relay WPCR. The energy supplied to relay WPCR by the source of indication energy is insufficient to retain relay WPCR in its picked-up position, and accordingly relay WPCR releases and its back contact 23 closes. However, the connection of the low voltage source to conductors 9 and 10 is now interrupted by the neutral contacts 24 and 25 of relay WR, and also by the reversal of the polar contacts 21 and 30 of relay WR.

When the contacts 24 and 25 of relay WR pick up, they establish a circuit to energize the switch motor operating circuit so as to operate the switch to its reverse position. This circuit is traced from the positive brush 5 of the generator G, over pole changing contact 11, front contact 15 of relay WCR, through conductor 10, front contact 24 of relay WR, reverse polar contact 32 of relay WR, switch operated contacts 34 and 35, field 38 of motor M, reverse polar contact 40 of relay WR, armature 41 of motor M, thermal resistance 42 and the pick-up winding 43 of overload relay OR in multiple, front contact 25 of relay WR, through conductor 9, over front contact 16 of relay WCR, and over pole changer contact 12 to the negative brush 6 of the generator G. The motor armature and its field winding are energized in series and the various parts are arranged so that the motor operates to move the switch W to its reverse position.

The contact 35 is operated in accordance with the movement of the switch and is arranged so that it engages contact 34 in all positions of the switch except the reverse position, and so that it engages a contact 36 in all positions of the switch except the normal position. Accordingly, when the switch completes its movement to its reverse position, contact 35 is moved out of engagement with contact 34 to interrupt the circuit traced above for supplying energy to the motor M and the motor ceases to operate. Interruption of the motor circuit by contact 35 removes the load from the generator G, and the resulting reduction in the effort required to operate the generator indicates to the operator that the switch has completed its movement, and that further operation of the generator is unnecessary. When the generator speed decreases sufficiently, the output voltage falls below that required to retain relays WCR and WR picked up, and these relays then release. Assuming that the switch W has completed its movement to the reverse position and contacts 22 and 29 have been operated to their reverse position, a circuit is now established to energize relay WPR. This circuit may be traced from positive terminal B, through rectifier K, over reverse polar contact 21 of relay WR, reverse contact 29, back contact 25 of relay WR, through conductor 9, over back contact 16 of relay WCR, winding of relay WPR from right to left, over back contact 15 of relay WCR, conductor 10, back contact 24 of relay WR, back contact 23 of relay WPCR, reverse contact 22,

reverse polar contact 30 of relay WR, and through resistor R to terminal C. Accordingly, relay WPR is energized with energy of reverse polarity and its polar contacts move to their reverse position and its neutral contacts pick up. Front contact 17 and reverse polar contact 18 of relay WPR then cooperate to control reverse indication lamp 59 to show that the switch is in its reverse position.

When the switch is in its reverse position, the operator may move the switch to its normal position by moving the control lever L to its normal position and operating the generator. When the generator output voltage becomes sufficient, relay WCR picks up and connects conductors 9 and 10 to the brushes 5 and 6 of the generator through contacts 11 and 12 of the lever L. Relay WPR is released and positive high voltage energy flows through conductor 9, over back contact 25 of relay WR, reverse contact 29, over reverse polar contact 21 of relay WR, but is prevented from flowing to terminal B by rectifier K.

Relay WPCR picks up because of the high voltage across its terminals, and its back contact 23 disconnects the source of indication energy from the line conductors from which relay WR now receives sufficient energy to operate its contacts and the polarity of the high voltage energy is such that its polar contacts move to their normal position. When the neutral contacts of relay WR pick up, the supply of high voltage energy to relay WPCR is interrupted, and relay WPCR releases. However, as previously explained, the closing of back contact 23 of relay WPCR does not connect the source of indication energy to conductors 9 and 10 since the circuit is further interrupted by the picking up of contacts 24 and 25 of relay WR.

Also, when contacts 24 and 25 of relay WR pick up, a circuit is established to supply high voltage energy to the motor M, so as to operate the switch from its reverse to its normal position. This circuit is traced from the positive brush 5 of generator G, over pole changing contact 11, front contact 16 of relay WCR, conductor 9, front contact 25 of relay WR, through thermal resistor 42 and pick-up winding 43 of overload relay OR in multiple, motor armature 41, over normal polar contact 40 of relay WR, contacts 35 and 36, through the field winding 38, normal polar contact 32 of relay WR, front contact 24 of relay WR, through conductor 10, over front contact 15 of relay WCR, and pole changing contact 12 of lever L to the negative brush 6 of generator G. The motor armature and its field winding are energized in series and the parts are arranged so that the motor operates to move the switch W to its normal position. When the switch completes its movement to its normal position, contact 35 is moved out of engagement with contact 36 and interrupts the circuit traced above for supplying energy to the motor M and the motor ceases to operate. The removal of the load from the generator indicates to the operator that the switch has completed its movement and further operation of the generator is unnecessary. When the generator output voltage drops below the value necessary to retain relays WCR and WR picked up, these relays release, and again establish a circuit for energizing relay WPR. Assuming that the switch completed its movement to its normal position, restoring contacts 22 and 29 to their normal position, energy of normal polarity is supplied to relay WPR by the circuit previously traced for the normal condition of the apparatus.

Accordingly, the polar contacts of relay WPR move to their normal position, and the neutral contacts pick up. Front contact 17 and normal polar contact 18 of relay WPR then establish the circuit of the normal indication lamp 49.

The thermal resistance 42, which is included in series with the circuit for supplying energy to the motor, has a positive thermal coefficient of resistance, that is, the resistance of the unit increases as the temperature of the material of which it is constructed increases.

The terminals of the pick-up winding 43 of the overload relay OR are connected across the thermal resistance 42, while means are provided to shunt the high resistance holding winding 19 when the contacts of this relay are released and to energize the holding winding 19 from the conductors 9 and 10 when the overload relay contacts are picked up.

20 The relay OR is equipped with contacts of the make-before-break type, and as shown, the right-hand terminal of the holding winding 19 is connected to movable contact 45, which, when released, engages stationary contact 46 which is connected to the left-hand terminal of the winding 19. Accordingly, as long as the contacts of relay OR are released, the holding winding 19 of relay OR is short circuited by the circuit controlled by contacts 45 and 46. As the winding 19 is short circuited when the relay contacts are released, the relay contacts are rendered slow in picking up and the overload relay will not respond to momentary surges in the current in the motor circuit.

35 As previously explained, the energy supplied to the motor M is supplied over the circuit which includes in series therewith the resistor 42 and the overload relay pick-up winding 43 in multiple. On the supply of energy to the motor M a portion 40 of the energy supplied to the motor is supplied through the pick-up winding 43 of relay OR. As a result of the supply of energy to the motor M, the resistance 42 becomes heated and its resistance increases so that there is a corresponding 45 increase in the value of the current supplied through the pick-up winding 43 of relay OR.

The various parts of the apparatus are arranged and proportioned so that under normal conditions most of the energy supplied to the motor is supplied through the resistor 42, while the current supplied through the winding 43 of relay OR is of too small value to pick up the relay contacts. Accordingly, the contacts of the relay OR remain released and contact 20 maintains the circuit for connecting the winding of relay WR across the conductors 9 and 10 so that the neutral contacts 24 and 25 of relay WR remain picked up and maintain the supply of energy to the motor until the switch completes its 60 movement and causes contact 35 to interrupt the circuit of the switch motor.

The various parts of the equipment are also arranged and proportioned so that if the motor M draws current of unusually high value for an 65 abnormally long period, as occurs when movement of the switch is obstructed, the resistance 42 will become heated to a temperature such that its resistance increases to a degree effective to cause the current supplied through the winding 43 of relay OR to be great enough to pick up the relay contacts.

On movement of the contacts of relay OR towards their picked-up position, contact 47 engages contact 45 to thereby establish a circuit to 75 energize the holding winding 19 from the con-

ductors 9 and 10, while contact 47 moves contact 45 out of engagement with the stationary contact 46 to interrupt the circuit short circuiting the winding 19.

If the switch is being moved to its normal position at the time the overload condition occurs, energy flows through the pick-up winding 43 of relay OR from right to left, and if the switch is being moved to its reverse position at the time the overload condition occurs, energy flows through the winding 43 from left to right. The right-hand terminal of the holding winding 19 of relay OR is connected to conductor 9 by a circuit including contacts 45 and 47, and the left-hand terminal of winding 19 is connected to conductor 10 by a circuit having in series therewith a resistor 44, so that when high-voltage energy of normal polarity is supplied to conductors 9 and 10 to operate the switch to its normal position and an overload condition causes relay OR to pick up, energy will flow through the holding winding 19 of relay OR from right to left, while when high-voltage energy is supplied to conductors 9 and 10 to operate the switch to its reverse position and an overload condition causes relay OR to pick up, energy will flow through winding 19 from left to right.

Accordingly, the energy supplied to the holding winding 19 of relay OR flows through this winding in the same direction as the energy which is supplied to the pickup winding of the relay. As a result, the energy supplied to the pick-up and holding windings of this relay cause flux of the same polarity to be developed in the relay core so that on picking up of the relay contacts, and resultant supply of energy to the relay holding winding, the relay contacts are maintained picked up.

In addition, on picking up of the contacts of relay OR, its contact 20 interrupts the circuit of the winding of relay WR so that neutral contacts 24 and 25 of this relay release and interrupt the supply of energy to the motor and the pick-up winding of relay OR. Back contacts 24 and 25 of relay WR connect the source of indication energy to the line, but the high voltage causes relay WPCR to pick up and isolate this portion of the circuit, as previously described. Relay OR remains picked up, however, by energy supplied to the holding winding 19 as long as the generator at the office is operated.

The resistor 44 which is in series with the holding winding serves to limit the flow of low-voltage indication energy through the holding winding 19, and serves to limit the current flow at the moment the overload relay contacts pick up, since when contact 47 engages contact 45, and before contact 45 moves out of engagement with contact 46, a connection is established between conductors 9 and 10. This circuit is interrupted as soon as contact 45 is moved away from contact 46, but the resistance 44 prevents excessive current flow in this circuit during the momentary period in which the circuit is established.

When an overload condition occurs, and relay OR picks up, thereby causing relay WR to release, the load of the switch motor is removed from the generator G, and the operator is made aware of an abnormal condition by the lessening of the effort required to operate the generator. He may then cease to operate the generator, and if the switch has become stalled at some point in transit, no indication will be received, since contacts 22 and 29 will be open.

He may then place the control lever L in the other position, and again operate the generator to move the switch to its other position. Since no energy was supplied to relay OR when the operator ceased the operation of the generator, relay OR will release and interrupt the previously traced circuit for energizing the holding winding 19 from conductors 9 and 10.

Back contact 29 of relay OR establishes the circuit for energizing relay WR, so that when high-voltage energy is again supplied over conductors 9 and 10, relay WR will pick up, and if the polarity of the energy differs from that previously supplied, the polar contacts of relay WR will move to their corresponding positions and will establish circuits to cause the motor to move the switch away from the obstruction.

From the foregoing it will be seen that this system is arranged so that on picking up of the contacts of overload relay OR a circuit is established to energize the holding winding of the relay from the control wires to thereby maintain the relay contacts picked up, while a contact of the overload relay interrupts the circuit of the switch control relay WR to cause it to interrupt the circuit of the switch motor.

It will also be seen from the foregoing that this system provides means for the control and indication of an electric track switch which has as its source of operating energy a hand operated generator, using only two conductors between the control office and the location of the switch.

Although I have herein shown and described only one form of a switch control and indication system embodying my invention, it is understood that various changes and modifications may be made therein within the scope of the appended claims without departing from the spirit and scope of my invention.

Having thus described my invention, what I claim is:

1. A system for the remote control and indication of a railway track switch over a pair of conductors extending from a control office to the switch location comprising a hand operated direct current generator, a transfer relay having its winding connected across the terminals of said generator, pole changer contacts for selecting the direction of movement of the track switch, and a low resistance indication relay, all located at said office; a high resistance polar neutral control relay having its winding connected across said conductors, a switch machine having a motor for operating the track switch and contacts for indicating its position, and a low voltage source of energy, all at the switch location, the voltage of said source being insufficient to operate said control relay; a circuit over which said indication relay is normally energized by current from said low voltage source to indicate the position of the switch at said office including back contacts of said transfer relay, said conductors, back neutral and polar contacts of said control relay, and said switch position indicating contacts, normal and reverse operating circuits for said switch motor supplied with current from said generator in response to its hand operation including said pole changer contacts, front contacts of said transfer relay, said conductors and front neutral and polar contacts of said control relay, and means at the switch location for opening said normal or reverse operating circuit to indicate at the office the termination of the movement of the track switch by the

resulting decrease in the effort required to operate said generator.

2. A system for the remote control and indication of a railway track switch over a pair of conductors extending from a control office to the switch location comprising a hand operated direct current generator, a transfer relay having its winding connected across the terminals of said generator, pole changer contacts for selecting the direction of movement of the track switch, and a low resistance indication relay, all located at said office; a high resistance polar neutral control relay having its winding connected across said conductors, a switch machine having a motor for operating the track switch and contacts for indicating its position, and a low voltage source of energy, all at the switch location, the voltage of said source being insufficient to operate said control relay; a circuit over which said indication relay is normally energized by current from said low voltage source to indicate the position of the switch at said office including back contacts of said transfer relay, said conductors, back neutral and polar contacts of said control relay, and said switch position indicating contacts, and normal and reverse operating circuits for said switch motor supplied with current from said generator in response to its hand operation including said pole changer contacts, front contacts of said transfer relay, said conductors, and front neutral and polar contacts of said control relay.

3. A system for the remote control and indication of a railway track switch over a pair of conductors extending from a control office to the switch location comprising a hand operated direct current generator, a transfer relay having its winding connected across the terminals of said generator, pole changer contacts for select-

ing the direction of movement of the track switch, and a low resistance indication relay, all located at said office; a high resistance polar neutral control relay having its winding connected directly across said conductors, a quick acting relay having its winding connected across said conductors over back contacts of said control relay, a switch machine having a motor for operating the track switch and contacts for indicating its position, and a source of indication current the voltage of which is not sufficient to operate said control relay or said quick acting relay, all at the switch location; a circuit over which said indication relay is normally energized by current from said source to indicate the position of the switch at said office including back contacts of said transfer relay, said conductors, back neutral and polar contacts of said control relay, said switch position indicating contacts, and a back contact of said quick acting relay, and normal and reverse operating circuits for said switch motor supplied with current from said generator in response to its hand operation including said pole changer contacts, front contacts of said transfer relay, said conductors, and front neutral and polar contacts of said control relay.
